UNITED STATES PATENT OFFICE.

WILLARD A. MORRISON AND FRED L. BRYANT, OF CHICAGO, ILLINOIS.

CLAMP FOR METAL BEDSTEADS.

SPECIFICATION forming part of Letters Patent No. 693,562, dated February 18, 1902.

Application filed June 24, 1901. Serial No. 65,790. (No model.)

To all whom it may concern:

Be it known that we, WILLARD A. MORRISON and FRED L. BRYANT, citizens of the United States, residing at Chicago, in the county of Cook and State of Illinois, have invented a certain new and useful Improvement in Clamps for Metal Bedsteads, of which the following is a full, clear, concise, and exact description, reference being had to the accompanying drawings, forming a part of this specification.

Our invention relates to a metal bedstead, our object being to provide improved means for securing the side rails of the bedstead to the end pieces.

Metal bedsteads as commonly constructed comprise a pair of end pieces each having two uprights or posts suitably connected together, the end pieces being connected by means of a pair of side rails, the ends of which are adapted to be secured to the uprights or posts of the end pieces. In one form of bedstead as commonly employed heretofore a casting has been provided upon each end of the side rail, said casting each being provided with a bore through which the upright or post of the end piece is adapted to pass, the casting being secured at the desired height upon the post by means of a set-screw. This construction is objectionable, since the set-screw tends to mutilate the post and does not afford an efficient gripping-surface, and, moreover, when it is desired to remove the side rail it is necessary to slip the casting off the end of the post, thus necessitating the removal of the casters. The removal of the side rails in this form of bed-plate is thus difficult and inconvenient. In another form of metal bedstead which has been extensively used heretofore a chilled casting has been molded about the post of the end piece, which casting is adapted to receive and support the end of the side rail, usually by the provision of a slot in the casting adapted to receive a tongue carried upon a casting secured to the end of the side rail. This construction is objectionable, due to the fact that the casting which is molded to the post is chilled and is therefore very difficult to tool. Any inaccuracy in the formation of the casting or of the slot therein throws the bedstead out of alignment and destroys the rigidity of the structure, which ri-

gidity is a desirable feature in a metal bedstead.

It is of prime importance in the construction of a metal bedstead that the side rail should be rigidly secured to the upright or post, so that no lost motion is permitted between the side rail and the posts. Otherwise the strain imposed upon the structure will cause the parts to wobble.

In accordance with the present invention we provide a clamp adapted to engage the uprights or posts, and this clamp is provided with two jaws or members which are hingedly connected together, or at least connected together in some loose manner, at the outer edge, while the inner end of one of the jaws is fixedly and rigidly secured to the side rail. A clamping device, as a screw, is associated with the inner end of the other jaw, whereby the jaws may be pressed together to thus securely clamp the side rail to the post or upright. By thus mounting one of the jaws fixedly and rigidly upon the side rail any lost motion between the side rail and the clamp is prevented, and by hinging the two jaws together at the outer edge and providing a clamping device at the inner end of the movable jaw the two jaws are rigidly secured together and to the upright or post, thus absolutely preventing any lost motion and producing a bedstead or frame possessing absolute rigidity and doing away entirely with any tendency of the bed to wobble.

We are aware that it has been proposed heretofore to provide a clamp consisting of two jaws adapted to be secured together and to the side rails by means of a single bolt, and we disclaim such a structure.

We have illustrated our invention in the accompanying drawings, in which—

Figure 1 is an end view of the end piece, showing the side rails in position. Fig. 2 is a side view of the bedstead. Fig. 3 is a detail view of the end of the side rail and a portion of the post. Fig. 4 is a sectional view on line 4 4, Fig. 3. Fig. 5 is a sectional view on line 5 5, Fig. 6. Fig. 6 is a sectional view on line 6 6, Fig. 5.

Like letters refer to like parts in the several figures.

The end piece comprises a pair of uprights or posts *a a'*, joined together in any suitable

manner—as, for instance, by the cross-pieces $a^2 a^3 a^4$ and the uprights $a^5 a^6$. The usual casters $b b$ are illustrated as mounted upon the lower ends of the posts. The side rail b' carries upon the ends the clamps $b^2 b^3$. Each of the clamps comprises two members or jaws $c c'$, one of the jaws c being secured to the end of the side rail, while the other jaw c' is movable and is hinged to the stationary jaw c .
 5 The lugs $c^2 c^3$ are carried upon the jaws $c c'$ and are provided with bores which rest in alinement and which receive a pin c^3 . The lugs and pin thus constitute a hinge about which the movable jaw c' may be swung. The
 10 jaw c' carries upon the edge opposite the hinge a bifurcated tongue or lip c^4 .

Secured to the side rail b' is a bracket d , to which is pivoted the end of a screw d' , carrying upon the end a thumb-piece c^6 and a
 20 washer c^5 . The pivoted screw is adapted to be swung into position so that the thumb-piece c^6 may force the washer c^5 against the lip c^4 to thus compress the post a between the two jaws of the clamp, and thus secure the
 25 side rail to the post. When it is desired to adjust the height of the side rail, the thumb-piece c^6 may be turned to release the movable jaw, and the clamp may thus be moved to the proper position upon the post, and the
 30 thumb-piece may then be turned to clamp the side rail in the new position.

In some instances we find it desirable to provide upon the post a locator to insure the placing of the clamp at a definite position.
 35 This locator may take the form of an engaging projection and recess, the projection being carried upon the post and the recess upon the clamp, or vice versa. As shown in Figs. 5 and 6, a pin f passes through the opposite
 40 walls of the post a , one end projecting beyond the exterior of the post and adapted to enter a recess or channel formed in the face of the stationary jaw of the clamp. The engagement of the pin and recess insures the placing
 45 of the side rail at a definite and predetermined height. For most bedsteads used for domestic purposes it is desirable to employ the locator, since the side rails should then be mounted at a definite height. For hospitals and other places where it may be desired
 50 to adjust the height of the side rail, the locator may be omitted, or, if desired, a plurality of locators may be employed to accommodate the clamp at different heights.

55 In Figs. 5 and 6 the movable jaw is shown

as constructed so that the same may be detached from the stationary jaw. The lugs c^2 of the jaw c' are cut away upon one side to leave the slots e^2 , and when the movable jaw is swung upon its pivot the lugs may be moved out of engagement with the pin c^3 and the movable jaw thus detached from the stationary jaw. The making of the movable jaw detachable facilitates manufacture and lessens the cost of production. 65

In Figs. 5 and 6 a modification of the pivotal mounting of the screw d' is shown. In this instance an opening e is provided through the wall of the side rail, and a recess is provided in the face of the stationary jaw c of the clamp. The pivoted end of the screw d' carries a pin e' , which is adapted to fit against the face of the side rail. In this manner the screw d' is pivotally mounted so that the same may be rocked back and forth as desired. 75

Having described our invention, what we claim as new, and desire to secure by Letters Patent, is—

1. In a bedstead, the combination with an upright or post, of a side rail, a clamp adapted to engage said upright or post and comprising two jaws or members hingedly connected together at the outer edges, the inner end of one of said members being rigidly secured to the side rail, and a clamping device 80 for forcing inward the inner end of the other jaw or member, whereby the side rail is securely clamped to the post or upright and lost motion is eliminated, substantially as described. 90

2. In a bedstead, the combination with the end pieces each comprising a pair of uprights or posts suitably connected together, of a pair of side rails, a clamp at each end of each of said side rails adapted to engage the respective uprights or posts, and each comprising two jaws or members hingedly connected together at the outer edge, the inner end of one of said members being rigidly secured to the side rail and a clamping device for forcing inward the inner end of the other jaw or member, substantially as described. 95 100

In witness whereof we have hereunto subscribed our names in the presence of two witnesses.

WILLARD A. MORRISON.
FRED L. BRYANT.
